UNITED STATES PATENT OFFICE.

BERNARD L. BRANDT, OF DUNDEE, MICHIGAN; SARAH A. BRANDT ADMINISTRATRIX
OF SAID BERNARD L. BRANDT, DECEASED.

SPRING TENSION DEVICE.

1,137,722.

Specification of Letters Patent. Patented Apr. 27, 1915.

Application filed January 27, 1912. Serial No. 673,899.

To all whom it may concern:

Be it known that I, BERNARD L. BRANDT, a citizen of the United States of America, residing at Dundee, in the county of Monroe 5 and State of Michigan, have invented certain new and useful Improvements in Spring Tension Devices, of which the following is a specification, reference being had therein to the accompanying drawings.

10 This invention relates to garment supporters and more particularly to suspenders.

The object of this invention is to provide a suitable spring tension device having new and useful features in its construction which 15 will be hereinafter specifically described and then claimed.

Reference will now be had to the drawing, wherein—

Figure 1 is a front elevation of a portion 20 of a pair of suspenders, partly broken away and partly in section, and Fig. 2 is a similar view showing a spring compressed.

In the drawing, the reference numeral 1 denotes a portion of the shoulder strap to an 25 end of which is connected a link 10 and connected to said link is a looped strap 11 providing a pocket. Secured in the lower end of the pocket is a bearing strip 3 held in position by eyelets 4, the bearing strip being 30 preferably formed of leather or other suitable flexible material. A tension cord 5 which is preferably formed of closely woven fabric material, round in cross section, is run through the eyelet 4, forming a loop 35 within the looped strap or pocket 11.

Sleeved upon the tension cord 5 within the pocket 11 is a coiled spring 12 having the

end convolutions thereof enlarged in diameter, as at 13, to seat upon the peripheral flanges 20 of thimbles 19 upon the cord 5. 40 These thimbles are normally inclined and engage the strip 3 at one side only, when the cord 5 is not under tension, as shown in Fig. 1, but when a pull comes upon the cord and the spring is compressed thereby, as shown 45 in Fig. 2, these thimbles will seat upon the eyelets and thus form extended guides for the cord so that there will be no possibility of its binding in the eyelet. The increasing of the diameter of the end convolutions of 50 the spring serves the same purpose as said coils will seat upon each other and form a tubular guide for the cord.

Having thus fully described my invention what I claim is:—

The combination with a strap having a loop at its end forming a pocket, of a bearing strip arranged within the lower end of said pocket, eyelets extending through the lower end of the pocket and said bearing 60 strip, normally inclined thimbles resting upon the inner ends of said eyelets, a cord extending through said eyelets and said thimbles and forming a tension loop within the pocket, and means encircling the cord of 65 said tension loop and said thimbles for maintaining said loop in an extended position within the pocket of said strap.

In testimony whereof I affix my signature in presence of two witnesses.

BERNARD L. BRANDT.
